UNITED STATES PATENT OFFICE.

WALTER VON NESSEN, OF BROOKLYN, NEW YORK, ASSIGNOR TO EFCOLITE CORPORATION, A CORPORATION OF NEW YORK.

DESIGN FOR A LIGHTING FIXTURE.

Application filed September 11, 1925. Serial No. 14,756. Term of patent 3½ years.

To all whom it may concern:

Be it known that I, WALTER VON NESSEN, a citizen of the German Republic, and a resident of Brooklyn, county of Kings, city and State of New York, have invented a new, original, and ornamental Design for Lighting Fixtures, of which the following is a specification, reference being had to the accompanying drawing, forming a part thereof.

In these drawings:

Figure 1 is a side elevational view of the lighting fixture,

Figure 2 is an inverted plan view of the lighting fixture, and

Figure 3 is a section taken on the line 3—3 of Figure 2.

I claim:

The ornamental design for a lighting fixture, substantially as shown.

WALTER VON NESSEN.
